UNITED STATES PATENT OFFICE

LLOYD B. ELLIOTT, OF SAN FRANCISCO, CALIFORNIA

GAME APPARATUS

Application filed July 16, 1928. Serial No. 293,258.

This invention relates to an improved football game apparatus, and has for its principal object the provision of means in which the elements of chance and skill are combined in such a manner that while the chances of one side or the other winning may remain undetermined until the last moment, yet the more skillful player has a slight advantage.

Another object of the present invention is to provide a game apparatus which is lined to simulate a football field, on the side of which is positioned a movable member adapted to be manipulated in turn by the players of the game to indicate the progress of a football team over the playing surface of the field.

A further object of the invention is to provide a game of the character described which is simple in construction, easy to play, economical to manufacture, highly entertaining, and a game in which interest may be provided for those who are interested in this class of athletic games.

A still further object is to provide a game board having a number of lines of different length and color, whereby the advancing or the retarding of the respective teams may be clearly and quickly determined.

A still further object is to provide in conjunction with a football game, a novel type of counting device which co-operates with the special markings on the field so as to facilitate the counting off accurately and rapidly the distance gained in an offensive or defensive movement.

Other objects and advantages will be apparent during the course of the following description.

In the accompanying drawings forming a part of this specification, and in which like numerals are employed to designate like parts throughout the same,

Figure 1 is a top plan view of the game constructed in accordance with my invention,

Figure 2 is a transverse vertical section of

the game board, with the counting device being shown in elevation,

Figure 3 is a sectional detail on an enlarged scale of a portion of the game board, and its co-operating counting element,

Figure 4 is a perspective view of the line marker, forming part of my invention,

Figure 5 is a similar fragmentary view of a portion of the block that supports the counting element, forming part of my device, and

Figures 6, 7, 8, and 9 are perspective views of two pairs of the counting dice that are used in conjunction with my football game board,

Figures 8 and 9 being perspective views of the remaining faces of the dice shown in Figures 6 and 7 respectively.

I am aware that football game apparatus of various natures have been previously patented, but none that I have studied discloses the unique arrangement of employing a novel type of counting device, that co-operating with the special markings on the field facilitates the counting off accurately and rapidly the distance gained in a defensive or offensive movement.

In Figure 1 there is represented a board 8 which is marked and ruled to simulate a football field, the goals being at the ends of the board, and designated by the numerals 9 and 10, the field intermediate the goals being ruled with parallel cross lines to indicate the one hundred yards between goals. The reference character G designates the goal line which at each end of the field is placed ten yards from the line wherein the goal posts 9 and 10 rest. The several lines are successively numbered beginning at each goal from 1 to 50, the latter being the center line, equally distant from the goals.

Secured to the game board 8 and extending longitudinally thereof is a base 12 which has provided therein spaced parallel grooves 13 and 14. As shown to advantage in Figures 2 and 5, the upper surface of the base is inclined, while the lower surface is in parallel

ism with the game board. The grooves 13 and 14 are formed at an angle in said base so as to present to view the marking on the counting device.

Within the upper groove 13 there is slidably mounted a substantially triangular element 15 which has positioned therein and at right angles thereto a wire 16 adapted to carry upon its upper end a freely rotatable knob 17 having markings thereon, 1, 2, 3, 4 indicating the "downs" of the game, while on the opposite end of the wire or rod 16 there is positioned a globular member designating a football 18.

In the lower groove 14 there is slidably positioned a strip 19 which has connected thereto a plate 20, which plate corresponds to the "yard line" used in a football game. This plate has indicia thereon, which for the purpose of clarity and a better understanding of the game, as the description proceeds will herein be specifically set forth.

As illustrated in Figure 3, there are two series of numerals on the upper plate, running from 1 to 9, while on the lower edge of the plate there are two series of numerals that include the designations 1, 3, 5, 7, 9. Intermediate the upper and lower sets of numerals there is provided a larger set of encircled numerals with the zero indicated in the center of the plate, and the numerals 2, 4, 6, 8, 10 being placed on each side of the zero, and extending substantially to the ends of the plate.

Referring to Figure 1, the special markings, namely the varying length of lines and colored lines, between each distance of five yards will be more specifically described in order that the co-operation between these particular markings and those enumerated on the plate may be readily understood.

It will be noted that the lines between each five yard distance vary as to length, and are further distinguished by different colors. For instance, as disclosed in Figure 3, considering the marking designated by the numerals 6, 7, 8 and 9, in the respective five yard blocks on the right side of the drawing, the short line 6 is colored green, the next longest line 7 is colored red, the third longest line 8 is colored black, while the longest line 9 is colored yellow. On the left side of the drawing the numerals and colors are reversed.

It will be evident that in counting five or ten yards or multiples thereof across the whole length of the gridiron, the plurality of lines of varying length and colors eliminates the necessity of a counting of yards, or an addition of numbers, as the movement from one color and length across the five yard line to the next color and length across the next five or ten yard line, will allow a quick and ready check of the gains or losses of the foot-

ball team during the course of the playing of the game.

It is to be noted that these specially marked lines will always be in alignment with the numerals that appear on the plate 20, irrespective of the distance over the game surface that the counting device is moved.

The numerals 21, 22, 23, 24, 25 and 26 designate areas herein referred to respectively as "Kick off", "Punt", "End run", "Line play", "Pass" and "Field goal", which areas are provided on the game board and are distinguished one from the other by particular lettering designating certain plays in the game to be decided by a throw of a certain pair of dice. There are six pairs of dice, and each die has a different marking thereon to distinguish it from the other die. Two pairs of dice are shown in Figures 6 and 7, and are designated by the numerals 27 and 28, respectively.

Each area is intended to hold a pair of dice when the same are not in use, and the particular area in which the respective pairs are adapted to rest is marked with a letter or number corresponding to the letter or number that appears on the dice.

For instance, the area 21 has the words "Kick off" thereon, with the letters K and R appearing in the upper corner of the area. One pair of the six pairs of dice is likewise marked, one with the letter K and the other with the letter R. The rest of the indicia in the area 21 designates different movements in the game.

Considering now area 22, or the "Punt" area this area has the letters N, N shown in the upper corner thereof. A second pair of dice, each of which is marked with the letter N is adapted to rest in the area 22. The same statement is applicable to various other areas that are designated by the respective numerals.

It will be noted from a consideration of Figure 6, that the pair of dice shown therein bear on all of the faces thereof, the letter L and differ one from the other in the numerals that appear on the respective faces. These numerals effect the total of yardage gained or lost in the play of the game. The letter L in this instance is marked on the six faces of the dice so that the L dice may be readily distinguished from the other pairs of dice and the player can readily select the same when he wishes to employ the dice in an offensive movement. The numerals set forth on the L dice and likewise on the other dice refer to the loss or gain experienced by the players of the game.

The rules governing the playing of this game should be determined by the rules at the time governing football contests, with the same number of points being scored by the players in this miniature game as are determined in the regular game of football.

In playing the game, the players choose

which of the goals 9 and 10 they are to defend, and then determine by any convenient means which side shall "Kick off". It is assumed that the player termed Black defends goal 10, while the player termed Brown defends goal 9.

Black now selects the "Kick off" dice from the area 21 and throws the same on the board. It will be assumed that the dice thrown by Black show on their uppermost faces, the markings K⁴⁰ and R¹⁰, indicating that Black has kicked off forty yards, and Brown has returned the ball ten yards. The ball is now in Brown's possession on his own 30 yard line. Brown places the rod 16 on the 30 yard line nearest the left hand side of the drawing and at the same time moves the plate 20 so that the zero is directly beneath the rod 16, and also actuates the knob 19 until the numeral 1 is uppermost thereon and in alignment with the zero on the plate.

Brown elects to try one of the plays designated in the areas 21 to 26, inclusive. Brown's object now is to advance the ball, if possible, towards Black's goal 10, and in order that Brown may continue in possession of the ball, it is necessary that he gain at least ten yards in four plays. If the ball is not advanced ten yards in four plays, then Brown must necessarily, according to the rules governing football, surrender the play to Black and he in turn can select the plays set forth in areas 21 to 26, inclusive and endeavor to reach Brown's goal 9.

Referring now to Brown's attempt to advance the ball, he first elects to try an "End run" and throws the E, E dice on the game board. Assuming that the face of one of the dice shows the numeral 7 and the other the numeral 8, a consideration of the legends in the area 23, will show that 7 is the low number and the number of yards gained in Brown's first attempt to rush the ball. The pair of dice, which are marked E, E are then returned to their proper area, and the knob is rotated to indicate second "down" and the football advanced to the black line marked 7, indicating that an advance of 7 yards has been made in the play.

The plate 20 remains in the same position, the numeral 7 thereon being in alignment with the black line 7 on which the football 18 is resting.

Brown may now elect to again try an "End run" and selects the two dice marked E, E which rest in area 23, and throws the same on the board. If, for instance, the numerals 6, 7 appear on the dice faces, it would indicate that Brown has made an advance of six yards, as the legend in the "End run" area shows that the low number, namely 6, is the number of yards gained. Therefore, as a result of this second play, Brown has made an advance of over ten yards in two tries, and

is now entitled to a further attempt of a gain of ten yards in four tries.

With each advance of ten yards, the counting device is moved in the grooved block, similar to the movement effected by the linesmen that hold the ten yard sticks in the regular game of football.

Brown now selects the dice from the "Line play" area. As a result of throwing the same, the numerals 3, 4 appear on the uppermost face of the dice which indicates that a gain of three yards has been made in the first attempt. He selects the same play, and again throws the dice, the numerals 2, 3 appearing, indicating that he has made two additional yards in his second attempt. He tries the same play, the numerals 1, 3 appearing, indicating that but one yard has been made. If he does not make the additional yards necessary, the ball will revert to Black, who will endeavor by a series of offensive movements to place the football over Brown's goal 9, and thus secure a "Touch down".

It is of course understood that there are numerous plays that can be made with this game that will be readily understood by one cognizant with the game of football, and it is thought that the description herein set forth of the respective plays is sufficient to clearly show how the ball can be advanced or retracted and it will be obvious that the employment of the varied colored means and the different lengths will enable the players to rapidly calculate and accurately ascertain the correct yardage in a minimum amount of time.

With this explanation it will be apparent how the various plays in the game may be made. As is evident, the element of chance is present throughout the game. However, familiarity with the game of football and skill in selecting the proper plays to be executed as governed by the situation that occurs, will often determine the winning of the game, and accordingly, give to the more skillful player, a slight advantage.

From the foregoing description, considered in connection with the accompanying drawing, it will be evident that I have devised a miniature entertaining and instructive football game that will warrant, for one of the players to prevail, considerable skill in a proper selection of plays.

It is to be understood that the form of my invention herewith shown and described is to be taken as a preferred example of the same, and that various changes relative to the shape, size, material and arrangement of parts may be resorted to without departing from the spirit of the invention, or the scope of the subjoined claim.

Having thus described my invention, I claim:

In combination with a game board simulating a football field and having markings

thereon consisting of lines of varying length and varying colors, a counting device mounted on said game board and comprising a grooved block, a rod holding element slidably mounted in one of the grooves of said block, the rod of said element having a counting knob on one end thereof and an element simulating a football on the opposite end thereof, said rod being adapted to pass over said indicia bearing plate upon the actuation of said rod holding element, whereby the number of yards gained or lost in the offensive or defensive movements of the game may be counted.

15 In testimony whereof I affix my signature.
LLOYD B. ELLIOTT.
